COUPLER

Edmund P. Kinne, Alliance, Ohio, assignor to
American Steel Foundries, Chicago, Ill., a corporation of New Jersey

Application June 17, 1931, Serial No. 545,063

24 Claims. (Cl. 213—151)

This invention pertains to coupler devices, and more particularly to a formation of coupler contours, such as the A. R. A. standard No. 10 contour, and the like.

5 Among the objects of the present invention is to provide a coupler contour adapted to effect well defined results not obtainable with the existing coupler contours and heretofore unknown. At the present time the existing contour lines 10 are determined preliminarily by standard requirements as to the desired horizontal and vertical angling of the couplers.

Under existing practice, however, it has been found, that although the standard vertical angling between couplers is substantially ideal for practical purposes, the coupler contour provided for effecting such results leads to undesirable free slack between cooperating couplers, which slack, in a train of substantial length and comprising a 20 large number of cars, is objectionable, undesirable and uncontrollable.

It is therefore an object of the present invention to provide novel means for decreasing the amount of free slack, yet at the same time maintaining the acceptable standard angling between 25 couplers.

In an embodiment selected to illustrate the invention, such results are effected by providing tapered portions on the front face of the knuckle, 30 such tapered portions being adapted to cooperate with the face of an adjacent coupler head, constructed in accordance with the present invention, for providing the desired vertical angling.

The invention comprehends the idea of providing a contour for the face of a coupler head 35 adapted to cooperate with the above described knuckle, wherein the cross-sectional area of the coupler face is increased over existing coupler heads. The tightening of the coupler face contour, heretofore desired but unobtainable, is effected in the present disclosure, and not only results in increasing the strength of the coupler head, but also in cooperating relation with the present improved knuckle, reduces the free slack.

45 It has also been found that under maximum horizontal angling of couplers the now standard requirement of approximately 15½ degrees is excessive and that from 10 to 12 degrees is quite sufficient.

50 The present invention therefore contemplates the idea of providing continuity of the above referred to contour of the coupler face to effect a tightening of the contour controlling horizontal angling of the couplers. This novel and improved contour results in increasing the

“gathering range” of couplers, that is, the ability of the contour of a coupler to pull the coupler head of an opposing coupler when the same are off-center. This increased “gathering range” is a very desirable feature.

With these and various other objects in view, the invention may consist of certain novel features of construction and operation, as will be more fully described and particularly pointed out in the specification, drawings and claims appended hereto.

5 In the drawings, which illustrate an embodiment of the device and wherein like reference characters are used to designate like parts—

Figure 1 is a fragmentary top plan view of a 15 coupler embodying the invention, the dotted lines indicating the corresponding A. R. A. contour;

Figure 2 is a fragmentary view in horizontal cross-section taken substantially through the longitudinal center line of adjacent couplers and 20 showing the relation between the same in buff;

Figure 3 is a fragmentary view in horizontal cross-section taken substantially through the longitudinal center line of adjacent couplers and showing the relation between the same in maximum horizontal angling; and 25

Figure 4 is a sectional elevation taken substantially in the plane as indicated by the line 4—4 of Figure 2, showing the couplers in vertically angled position;

Figure 5 is a fragmentary top plan view of a 30 coupler embodying a modification of the invention;

Figure 6 is a fragmentary top plan view of still another embodiment disclosing the present invention; and 35

Figures 7 to 9 inclusive are fragmentary top plan views of two opposing couplers made in accordance with Figure 1 of the drawings, disclosing the same in various positions when a 40 coupling is effected between the two in offset relation.

45 Referring first of all to the contour as shown in Figure 1, this contour is laid off from the longitudinal center line $y-y$ of the coupler and the transverse base line $x-x$. The contour of the knuckle is substantially that of the standard A. R. A. type of knuckle. The A. R. A. coupler contour referred to in this specification and the claims is the No. 10 contour as shown in Fig. 50 2523 on page 886 of the Car Builders Cyclopedic, 1931 edition. The coupler head 10 is defined substantially by the arc 12 merging into the arc 14, in turn merging into the arc 16, it being desired to provide additional metal on the stnd 55

ard A. R. A. contour shown in the dotted lines 18, say $\frac{1}{16}$ of an inch on the face of the coupler, though it is to be understood that any amount may be added. This amount, as shown, is defined by the line 20 merging into the curve 22, 24, 16, it being seen that the line 18 indicating the standard A. R. A. coupler contour merges into a curve 26 struck from substantially the same radius as the curve 22, the curve 26 merging into a curve 28 struck with substantially the same radius as curve 24, the curves 24 and 28 both merging into curve 16.

The face 18 of the A. R. A. type of coupler merges into curves 30 and 32 terminating in the end 34 disposed below the base line $x-x$, the termination of the guard arm determining the gathering range of the coupler. The face 20 of the improved coupler merges into the compound curve 36, 38, 40, it being seen that the curve 40 is a reverse curve from that shown at 38. The curve 40 crosses the x axis at substantially the same distance from the y axis as the point 42 is with reference to the y axis and terminates above the x axis and at a greater distance from the y axis. It may thus be said that the improved contour is tighter at similar points than the standard A. R. A. contour. It will be seen that the compound curve 38, 49 may follow the contour 32, it being only necessary that the curve fit the corresponding contour of the ear and knuckle of the adjacent coupler as shown in Figure 3 when the couplers are angled horizontally. The gathering range of the improved coupler is increased by carrying the curve 40 to a point 44 above the $x-x$ axis to the end 46 of the guard arm.

The knuckle 48 is pivoted substantially at the point 50 to the ears of the coupler, and this knuckle follows substantially the contour of that of the standard A. R. A. type of coupler. The improved type of knuckle, however, while following the plane of the standard A. R. A. type of knuckle, is beveled at 54 and 55 with substantially a 4°-40' taper, the width of the bevel being substantially the same as the amount of metal added to the face of the coupler. The beveled front face of the knuckle is provided so that the improved coupler may angle vertically substantially the same amount as the standard A. R. A. coupler, even though additional metal is added to the face of the coupler, that is, the bevel compensates for the addition of metal to the face of the coupler.

In operation of this type of coupler, it will be appreciated that the gathering range is materially increased, and additionally, there is a material decrease of the free slack defined between couplers, shown at 58 in Figure 2. That is, in buff the distance between the pulling faces of adjacent knuckles is decreased, this decrease of slack materially decreasing the strain put on the parts of the coupler when assuming a normal or pulling position, especially when it is appreciated that the slack is multiplied in a long train of cars.

As previously indicated, the new contour for the guard arm is disposed nearer the knuckle, thus decreasing the gauge distance and also extends forwardly beyond the corresponding standard A. R. A. contour. The decrease in the shortest distance between the guard arm and knuckle when the knuckle is closed is such a minimum as will permit normal operation of the coupler and maintain the coupler operative notwithstanding the increase of such distance incident

to the normal operation and limit of use of the coupler.

The new contour for the guard arm increases the gathering range of the coupler, i. e., the contour increases the capacity of the coupler for drawing a mating coupler from an offset position to a central position for effecting locking engagement of the knuckles of the opposing couplers, this new contour also tending to move a mating knuckle into open position upon its initial engagement therewith and tending to maintain said open position during coupling until the knuckles are moved into interlocking relation.

Figures 7, 8 and 9 disclose successive positions of the opposing couplers 100 and 102 having the guard arms 104, 106 and the knuckles 108, 110, respectively, when a coupling is to be effected with the same offset a distance "A". As shown in Figure 7, the knuckle 108 is in its normal full opened position and contacts guard arm 106 at a point 112 which is outside the pivot center 114 for knuckle 108 and therefore the force exerted in the direction of line 116 has a tendency to cause outward rotation of the knuckle while wedging action due to the angular contact at point 112 tends to cause a partial closing rotation of the knuckle 108 opposing the opening force represented by line 116 until the knuckle has reached a partial closed position as shown in Figure 8.

After reaching the position shown in Figure 8, the wedging action causing inward rotation of the knuckle is equalized by the force 116 tending to hold the knuckle 108 open, which latter force is represented in part by the frictional resistance at contact point 118. Inasmuch as the wedging action at point 118 no longer causes rotation of the knuckle 108, the same acts to draw the entire coupler 100 over, thereby decreasing the distance "A" between the couplers to the distance "B" shown in Figure 9. At this time knuckle 108 remains open sufficiently so as to pass inside of the nose of knuckle 110, as at 120, to effect locking engagement of the two knuckles. It is to be observed that during the entire coupling operation, the distance between couplers has been reduced to "B", while the distance through which the force represented by line 116 passes outside the pivot point 114 of knuckle 108 has been increased corresponding to "C", thereby increasing the tendency to hold knuckle 108 open to prevent the same from closing without effecting engagement with knuckle 110.

Figure 7 shows the opposing couplers apart a distance "A" which is substantially a maximum whereby a coupling may be effected for the given contour of the guard arms disclosed and for a corresponding distance apart for couplers with the standard A. R. A. contours, a coupling thereof cannot be effected under similar conditions.

Referring to Figure 3, the position of the parts is shown when a pair of couplers is angled horizontally. When this occurs the contour 40 fits the contour 12 of the ear of the adjacent coupler, and also the contour of the knuckle of the adjacent coupler.

In operation of a train, adjacent couplers will, due to different levels of adjacent cars in going up grades, etc., assume different vertical positions with respect to each other. In couplers now in use vertical angling of the couplers causes the knuckles to contact each other, and the adjacent heads at points, causing excessive wear at a plurality of points. That is, the knuckles will con-

tact at points 60, such as shown in the dotted line positions of Figure 4, these dotted line positions showing the contours of standard A. R. A. parts. In order to provide for vertical angling in the improved type of coupler, and also to prevent excessive wear at a plurality of points, the bevels 54 and 56 are provided which will contact the face 20 substantially uniformly when the knuckles are in their maximum angling position, the same 10 having substantial contact as at 62, when in this position.

In Figure 5 of the drawings, the disclosed contour of the coupler is such as to decrease the free slack and horizontal angling between opposing connector couplers. This coupler varies 15 from the previously described embodiment of the present invention, in that the contour 20a, corresponding to the contour shown in Figure 1 of the drawings, merges at a point 63 with the contour 32a of the guard arm of the standard A. R. A. coupler head. It will be seen that the distance between the nose of the knuckle and the face of the coupler head is decreased in accordance 20 with the above disclosure for decreasing the free slack.

In order to decrease the horizontal angling between couplers, the heel of the knuckle is extended from the line 64 of the old contour to line 65. The extension of the heel in this manner compensates for the modification of the contour of the coupler head, wherein the line 20a merges at the point 63. This increase in the size of the knuckle heel is substantially equal to that increase to the guard arm shown in Figure 1 35 of the drawings.

In Figure 6 of the drawings, a still further modification of the present invention is disclosed for effectively reducing free slack and horizontal angling between couplers. This is effected by extending the contour line of the bearing surface of the knuckle nose from 66 to 67, thereby not only decreasing the distance between the nose of the coupler and face of the coupler head, but likewise the gauge distance between the knuckle nose and guard arm of the 40 coupler head.

It is to be understood that I do not wish to be limited by the exact embodiment of the device shown, which is merely by way of illustration and not limitation, as various and other forms of the device will of course be apparent to those skilled in the art without departing from the spirit of the invention or the scope of the claims.

55 I claim:

1. In a coupler construction, the combination of a coupler head, a knuckle, said coupler head having a front face normally spaced from said knuckle to permit a limited amount of relative longitudinal translatory movement and vertical angling of a mating knuckle between said face and said first-mentioned knuckle, and means providing for an increased amount of vertical angling.

60 2. In a coupler construction, the combination of a coupler head, a knuckle, said coupler head having a front face normally spaced from said knuckle to permit a limited amount of relative longitudinal translatory movement and vertical angling of a mating knuckle between said face and said first-mentioned knuckle, and means on the face engaging portion of the knuckle to permit an increased amount of vertical angling.

65 3. In a coupler construction, the combination of a coupler head, a knuckle, said coupler head

having a front face normally spaced from said knuckle to permit a limited amount of relative longitudinal translatory movement and vertical angling of a mating knuckle between said face and said first-mentioned knuckle, said knuckle having portions of the face engaging portion thereof so disposed as to permit an increased amount of vertical angling.

5 4. In a coupler construction, the combination of a coupler head, a knuckle, said coupler head having a front face normally spaced from said knuckle to permit a limited amount of relative longitudinal translatory movement and vertical angling of a mating knuckle between said face and said first-mentioned knuckle, said knuckle 10 having portions of the face engaging portion thereof angularly disposed in relation to the plane of the pulling face so as to permit an increased amount of vertical angling.

15 5. In a coupler arrangement, the combination of opposing couplers each having a coupler head and knuckle adapted to be disposed in engaging relation, each of said couplers being provided with a head having a front face normally spaced from the knuckle thereof to permit a limited amount of relative longitudinal translatory movement and vertical angling between said opposing couplers, and means providing for an increased amount of 20 vertical angling between said couplers.

25 6. In a coupler arrangement, the combination of opposing couplers each having a coupler head and knuckle adapted to be disposed in engaging relation, each of said couplers being provided with a head having a front face normally spaced from the knuckle thereof to permit a limited amount of relative longitudinal translatory movement and vertical angling between said opposing couplers, and means on the face engaging portion of the knuckles to permit an increased amount of 30 vertical angling between said couplers.

35 7. In a coupler arrangement, the combination of opposing couplers each having a coupler head and knuckle adapted to be disposed in engaging relation, each of said couplers being provided with a head having a front face normally spaced from the knuckle thereof to permit a limited amount of relative longitudinal translatory movement and vertical angling between said opposing couplers, said knuckles having portions of the face 40 engaging portion thereof so disposed as to permit an increased amount of vertical angling between said couplers.

45 8. In a coupler arrangement, the combination of opposing couplers each having a coupler head and knuckle adapted to be disposed in engaging relation, each of said couplers being provided with a head having a front face normally spaced from the knuckle thereof to permit a limited amount of relative longitudinal translatory movement and vertical angling between said opposing couplers, said knuckles having portions of the face 50 engaging portion thereof angularly disposed in relation to the plane of the pulling face so as to permit an increased amount of vertical angling between said couplers.

55 9. In a coupler arrangement, the combination of opposing couplers each having a coupler head and knuckle provided with a contour adapted to provide a limited amount of slack therebetween 60 throughout the central horizontal portions thereof and an increased amount of slack at the top and bottom thereof of an extent sufficient to provide increased vertical angling therebetween, said coupler knuckles having their buffing faces so 70 75

disposed as to provide for said increased amount of angling between said couplers.

10. In a coupler arrangement, the combination of opposing couplers each having a coupler head and knuckle provided with a contour adapted to provide a limited amount of slack therebetween throughout the central horizontal portions thereof and an increased amount of slack at the top and bottom thereof of an extent sufficient to provide increased vertical angling therebetween, said coupler knuckles having their buffing face formed with portions inclined in respect to the plane of their pulling face and extending toward the top and bottom thereof to provide for said increased amount of angling between said couplers.

11. In a car coupler comprising a coupler head, a knuckle pivoted thereto, a guard arm on said head opposite said knuckle, the shortest distance between said knuckle when the knuckle is closed and said guard arm being such a minimum as will permit normal operation of the coupler and maintain said coupler operative notwithstanding the increase of such distance incident to the normal operation and limit of use of the coupler.

12. In a car coupler, the combination of a coupler head, a knuckle pivoted thereto, a guard arm on said head opposite said knuckle, the shortest distance between said knuckle when the knuckle is closed and said guard arm being such a minimum as will permit normal operation of the coupler and maintain said coupler operative notwithstanding the increase of such distance incident to the normal operation and limit of use of the coupler, said coupler head having a front face normally spaced from said knuckle to permit a limited amount of relative longitudinal translatory movement and vertical angling of a mating knuckle between said face and said first-mentioned knuckle, and means providing for an increased amount of vertical angling.

13. In a car coupler, the combination of a coupler head, a knuckle pivoted thereto, a guard arm on said head opposite said knuckle, said coupler head having a front face normally spaced from said knuckle to permit a limited amount of relative longitudinal translatory movement and vertical angling of a mating knuckle between said face and said first-mentioned knuckle, means providing for an increased amount of vertical angling, the contour of said guard arm at its end being such and so arranged relative to said mating knuckle, in open position, that moving engagement therebetween tends to maintain said mating knuckle in said position until said knuckles are disposed relative to one another to interlock.

14. In a car coupler, the combination of a coupler head, a knuckle pivoted thereto, a guard arm on said head opposite said knuckle, said coupler head having a front face normally spaced from said knuckle to permit a limited amount of relative longitudinal translatory movement and vertical angling of a mating knuckle between said face and said first-mentioned knuckle, means providing for an increased amount of vertical angling, the contour of said guard arm at its end being such and so arranged relative to said mating knuckle, in open position, that moving engagement therebetween tends to maintain said mating knuckle in said position until said knuckles are disposed relative to one another to interlock.

15. In a car coupler, the combination of a coupler head, a knuckle pivoted thereto, a guard arm on said head opposite said knuckle, said coupler head having a front face normally spaced from

said knuckle to permit a limited amount of relative longitudinal translatory movement and vertical angling of a mating knuckle between said face and said first-mentioned knuckle, means providing for an increased amount of vertical angling, the contour of said guard arm outwardly of said front face comprising a curve merging into a second curve in the same direction of large radius with relation to the first-mentioned curve and a reverse curve, the contour of said guard arm at its end being such and so arranged relative to said mating knuckle, in open position, that moving engagement therebetween tends to maintain said mating knuckle in said position until said knuckles are disposed relative to one another to interlock.

16. In a car coupler, the combination of a coupler head, a knuckle pivoted thereto, a guard arm on said head opposite said knuckle, said coupler head having a front face normally spaced from said knuckle to permit a limited amount of relative longitudinal translatory movement and vertical angling of a mating knuckle between said face and said first-mentioned knuckle, means providing for an increased amount of vertical angling, the contour of said guard arm outwardly of said front face comprising a curve merging into a second curve in the same direction of large radius with relation to the first-mentioned curve and a reverse curve, the contour of said guard arm at its end being such and so arranged relative to said mating knuckle, in open position, that moving engagement therebetween tends to maintain said mating knuckle in said position until said knuckles are disposed relative to one another to interlock.

17. In a car coupler, the combination of a coupler head, a knuckle pivoted thereto, a guard arm on said head opposite said knuckle, said coupler head having a front face normally spaced from said knuckle to permit a limited amount of relative longitudinal translatory movement and vertical angling of a mating knuckle between said face and said first-mentioned knuckle, means providing for an increased amount of vertical angling, the contour of said guard arm at its end being such and so arranged relative to said mating knuckle, in open position, that moving engagement therebetween tends to maintain said mating knuckle in said position until said knuckles are disposed relative to one another to interlock, said guard arm contour being so disposed that the shortest distance between said knuckle when the knuckle is closed and said guard arm being such a minimum as will permit normal operation of the coupler and maintain said coupler operative notwithstanding the increase of such distance incident to the normal operation and limit of use of the coupler.

18. In a car coupler, the combination of a coupler head, a knuckle pivoted thereto, a guard arm on said head opposite said knuckle, said coupler head having a front face normally spaced from said knuckle to permit a limited amount of relative longitudinal translatory movement and vertical angling of a mating knuckle between said face and said first-mentioned knuckle, means providing for an increased amount of vertical angling, the contour of said guard arm outwardly of said front face comprising a curve merging into a second curve in the same direction of large radius with relation to the first-mentioned curve and a reverse curve, the contour of said guard arm at its end being such and so arranged relative to said mating

knuckle, in open position, that moving engagement therebetween tends to maintain said mating knuckle in said position until said knuckles are disposed relative to one another to interlock, 5 said guard arm contour being so disposed that the shortest distance between said knuckle when the knuckle is closed and said guard arm being such a minimum as will permit normal operation of the coupler and maintain said coupler operative notwithstanding the increase of such distance incident to the normal operation and limit of use of the coupler.

19. In a car coupler, the combination of a coupler head, a knuckle pivoted thereto, a guard 15 arm on said head opposite said knuckle, the contour of said guard arm at its end being such and so arranged relative to a mating knuckle, in open position, that moving engagement therebetween tends to maintain said mating knuckle in said 20 position until said knuckles are disposed relative to one another to interlock, said guard arm contour being so disposed that the shortest distance between said knuckle when the knuckle is closed and said guard arm being such a minimum as 25 will permit normal operation of the coupler and maintain said coupler operative notwithstanding the increase of such distance incident to the normal operation and limit of use of the coupler.

20. In a car coupler, the combination of a 30 coupler head, a knuckle pivoted thereto, a guard arm on said head opposite said knuckle, the contour of said guard arm outwardly of the front face of said coupler head comprising a curve merging into a second curve in the same direction with large radius with relation to the first-mentioned curve and a reverse curve, the contour of said guard arm at its end being such and so arranged relative to a mating knuckle in open position, that moving engagement therebetween tends to maintain said mating knuckle in said 35 position until said knuckles are disposed relative to one another to interlock, said guard arm contour being so disposed that the shortest distance between said knuckle when the knuckle is closed and said guard arm being such a minimum as will permit normal operation of the coupler and maintain said coupler operative notwithstanding the increase of such distance incident to the normal operation and limit of use of the coupler.

40 21. In a car coupler, the combination of a coupler head, a knuckle pivoted thereto, a guard 45 arm on said head opposite said knuckle, the contour of said guard arm outwardly of the front face of said coupler head comprising a curve merging into a second curve in the same direction with large radius with relation to the first-mentioned curve and a reverse curve, said guard arm contour being so disposed that the shortest 50 distance between said knuckle when the knuckle is closed and said guard arm is such a minimum

as will permit normal operation of the coupler and maintain said coupler operative notwithstanding the increase of such distance incident to the normal operation and limit of use of the coupler.

5 22. In a car coupler, the combination of a coupler head, a knuckle pivoted thereto, a guard arm on said head opposite said knuckle, said coupler head having a front face normally spaced from said knuckle to permit a limited amount of relative longitudinal translatory movement and vertical angling of a mating knuckle between said face and said first-mentioned knuckle, means providing for an increased amount of vertical angling, the contour of said guard arm outwardly of said front face comprising a curve merging into a second curve in the same direction of large radius with relation to the first-mentioned curve and a reverse curve, the shortest distance between said knuckle when the knuckle is closed and said guard arm being such a minimum as will permit normal operation of the coupler and maintain said coupler operative notwithstanding the increase of such distance incident to the normal operation and limit of use of the coupler.

10 23. In a car coupler, the combination of a coupler head, a knuckle pivoted thereto, a guard arm on said head opposite said knuckle, said coupler head having a front face normally spaced from said knuckle to permit a limited amount of relative longitudinal translatory movement and vertical angling of a mating knuckle between said face and said first-mentioned knuckle, means providing for an increased amount of vertical angling, the contour of said guard arm outwardly of said front face comprising a curve merging into a second curve in the same direction of large radius with relation to the first-mentioned curve and a reverse curve.

15 24. In a car coupler, the combination of a coupler head, a knuckle pivoted thereto, a guard arm on said head opposite said knuckle, said coupler head having a front face normally spaced from said knuckle to permit a limited amount of relative longitudinal translatory movement and vertical angling of a mating knuckle between said face and said first-mentioned knuckle, means providing for an increased amount of vertical angling, the contour of said guard arm outwardly of said front face comprising a curve merging into a second curve in the same direction of large radius with relation to the first-mentioned curve and a reverse curve, the contour of said guard arm at its end being such and so arranged relative to said mating knuckle, in open position, that moving engagement therebetween tends to maintain said mating knuckle in said position until said knuckles are disposed relative to one another to interlock.
